UNITED STATES PATENT OFFICE.

HARRY A. WACKERLY, OF ALLIANCE, OHIO, ASSIGNOR TO THE MORGAN ENGINEERING COMPANY, OF ALLIANCE, OHIO.

ELECTRIC-MOTOR-CONTROL SYSTEM.

1,388,906.

Specification of Letters Patent. Patented Aug. 30, 1921.

Application filed July 21, 1920. Serial No. 397,820.

To all whom it may concern:

Be it known that I, HARRY A. WACKERLY, a citizen of the United States, and a resident of Alliance, in the county of Stark and State 5 of Ohio, have invented certain new and useful Improvements in Electric-Motor-Control Systems; and I do hereby declare the following to be a full, clear, and exact description of the invention, such as will enable others 10 skilled in the art to which it appertains to make and use the same.

This invention relates to improvements in electric motor control systems; and more particularly to means for automatically controlling the limit of travel of machinery, such as hoisting means operated by an electric motor, one object of the invention being to provide efficient means for preventing overtravel of the mechanism, such as a hoist, 20 by automatically stopping the driving motor at a predetermined point in the travel of the hoist or other member of machinery driven by said motor; to so construct and arrange the switch devices and circuits which 25 they control that said switches shall be reset automatically when the motor circuit is reversed, and to so construct and arrange said means that the action of the switches shall be quick, positive and efficient and 30 caused to operate in proper succession to effect the desired results.

A further object is to so construct limit switch mechanism in a system of electric motor control, that said mechanism shall be 35 operated mechanically by a part driven by the motor to effect the stopping of the motor and so that it will be operated electrically in effecting resetting of said mechanism.

A further object is to provide electrically 40 actuated means coöperable with limit switch mechanism which will operate automatically to insure quick shifting and intimate engagement of contacts of the switch devices when the same are operated to effect the stopping 45 of the driving motor, and which will also operate automatically to shift the switch devices in the resetting of the latter.

With these and other objects in view, the invention consists in certain novel features 50 of construction and combinations of parts as hereinafter set forth and pointed out in the claims.

In the accompanying drawings; Figure 1 is a diagrammatical view illustrating the arrangements of circuits and devices when my

improvements are applied to motor driven hoist mechanism; Figs. 2, 3, 4, 5, 6 and 7 are diagrammatical views illustrating the operation of the mechanism; Fig. 8 is an enlarged view in elevation showing the construction and arrangement of the limit switches; Fig. 9 is a view taken at right angles to Fig. 8, the casing being shown in section, and Fig. 10 is a detail view showing the cross bar with which the weight is connected.

In Fig. 1 of drawing, I have illustrated a controller at 1 provided with suitable contacts whereby shifting of the circuits through the resistance and the motor windings may 60 be effected,—said controller being provided with suitable step resistance elements indicated at 2 and 3 and with a permanent resistance 4 for the armature circuit. Conductors are indicated at 5, 6, 7, 8 and 9, and 65 the conductor from the positive side of the source of electrical supply is indicated at 10 as connected with the conductor 5. The conductor 11 from the negative side of the 70 source of electrical supply is connected with 75 the controller. The conductors 5 and 9 are connected, respectively, with the respective terminals of the solenoid of a brake indicated at 12, and this circuit (indicated at 80 85 80) also includes, in series, the coil of a solenoid 14, which is series wound with the same size wire as that of the brake solenoid. The solenoid 14 is movable as will be more fully hereinafter described and above it, a 90 fixed solenoid 15 is located and so wound (with the same size wire as that of the solenoid 14 and the brake solenoid) that poles of like sign of the two solenoids 14 and 15 will, normally, be presented to each other and result in a repelling tendency to cause 95 movement of the solenoid 14 for a purpose to be hereinafter explained. One terminal of the solenoid 15 is connected by a conductor 16 with the conductor 7 and the other terminal of said solenoid 15 is connected by a 100 connector 17 with a contact block 18 of a service limit switch A. This limit switch includes also a contact block 19 with which the contact block 18 coöperates, and also coöperating contact blocks 20 and 21. The terminals 105 of a resistance 22 are connected respectively with the contact blocks 18 and 19 and the latter is connected by a conductor 23 with the contact block 20. The contact block 21 is connected by a conductor 24 with the contact 110

block 25 of an emergency limit switch B and the latter also includes a contact block 26 coöperable with the contact block 25, and contact blocks 27 and 28 coöperable with each other.

The contact block 19 of limit switch A is connected by a conductor 29 with one side of the armature 30 of a driving motor and the other side of said armature is connected by a conductor 31 with the contact block 26 of the limit switch B and said contact block is connected by a conductor 32 with the contact block 27. The contact block 25 of limit switch B is connected by 10 a conductor 33 with a conductor 34,—one end of the latter being connected with one terminal of the field coil 35 of the motor and the other end of said conductor 34 is connected with the conductor 8. The 15 other terminal of the field coil is connected by a conductor 36 with the conductor 8 and said conductor 36 is connected by a conductor 37 with a resistance 38, the latter being connected, through a conductor 39 with the 20 contact block 28 of the limit switch B.

The conductors 6 and 8 (with which the conductors 34 and 36 leading from the field terminals are connected) are connected, by conductors 40 and 41 with the controller 20 and the conductors 7 and 9 are connected by conductors 42 and 43 with the controller, whereby the shifting of the circuit connections through the motor and the coil of solenoid 15 may be effected.

The limit switches A and B and the solenoids 14 and 15 may be located in a frame or casing 44 as shown in Figs. 8 and 9 and this frame or casing may be provided with suitable feet or supports 45. Standards 46 are located in the lower portion of the frame and provide bearings for the bell-cranks A¹ and B¹ of the limit switches A and B, the contacts 19—20 and 26—27 of these switches being preferably made of carbon and 45 clamped in holders 47—48 and 49—50 having threaded or other adjustable connection with and forming, in effect, portions of the bell-cranks of the switches, and said contacts and their holders are electrically separated from the remaining portions of the bell-cranks and their supports, by means of 50 insulators 51. The stationary contacts 18, 21, 25 and 28 of the limit switches may be made of copper and are supported by the 55 frame 44 and electrically separated from the latter by means of insulators 52. The bell-cranks of the limit switches are provided with arms 53 connected by a cross bar 54, the ends of which are loosely mounted on 60 the arms 53 of the respective switches and the intermediate portion of said cross bar is provided with a series of perforations 55,—in any of which a cord 56 may be connected. This cord carries a suspended 65 weight 57 to be engaged and lifted by a part

58 on a member of hoisting mechanism, as indicated at 59.

The clamps or holders 48 and 50 which carry the contacts 20 and 27 of the respective limit switches, are provided with lugs 70 60, 61, and these lugs are connected by a cross bar 62 pivotally connected therewith. The cross bar 62 is made of fiber and comprises two parallel members, between which a coupling member 63 is pivotally connected 75 in proximity to the connection of said cross bar with the lug 60 on the clamp or holder 48 on the bell-crank of switch A. A link 64 is pivotally connected with the movable solenoid 14 and, through the medium of the 80 coupling 63 with the cross bar 62, and the fixed solenoid 15 is secured to the casing over the movable solenoid 14. It will be observed that by means of the construction and arrangement of limit switches, as above 85 described, said switches will normally be maintained in the positions shown in Figs. 1, 8 and 9 by the action of the weight 57, and that when said weight is raised by the upward travel of the hoisting means, the 90 switches will be shifted. As the solenoids 14 and 15 are so wound that one will repel the other, the movable solenoid 14 when free to descend, will exert sufficient force on the switches to shift them quickly and cause the movable contacts to firmly engage the fixed contacts. Owing to the connections above described, between the two limit switches A and B, and the connection of the 95 cross bar 62 with the movable solenoid, the 100 switch A will close the circuit at contacts 20—21 prior to the closing of a circuit at 27—28 by movement of the bell-crank of switch B. The reason for such successive operation of the two limit switches will be 105 clearly understood from the following description of the operation of my improvements and the circuits and devices with which they coöperate.

In Fig. 2 of the drawing is shown the 110 arrangement of the circuits when both limit stops are in normal positions, the circuits being such that the field and armature of the motor are in series with each other and in series with the solenoids 14 and 15 and the 115 solenoid of the brake,—the step resistance of the controller being also shown in this same circuit. When the weight 57 is raised by the upward travel of the hoisting means, the bell-crank of the service limit switch A 120 will first be shifted to separate the contacts 18—19 and close the contacts 20—21. This shifting of the switch A will operate to short-circuit the armature of the motor, (as shown in Fig. 3) causing the same to stop 125 quickly by reason of the dynamic braking effect produced, as will be readily understood. The same shifting of the switch A will, in addition to short-circuiting the armature, insert the resistance 22 to choke an 130

excessive current which would otherwise flow through the field and solenoid windings, as also indicated in Fig. 3. Immediately after the switch A has been shifted, 5 producing the results just described, the emergency switch B will be shifted as previously explained, thus separating the contacts 25—26 and closing the contacts 27—28. The armature, field, and resistance 38 are 10 now connected in a closed circuit as indicated in Fig. 4,—both switches having been tripped, and a quick stop of the motor is insured, with the controller handle in any position or in off position or even if the line 15 voltage fails about the time the weight 57 is lifted by the hoisting means.

To effect the lowering of the hoisting mechanism, the controller will be operated to reverse the current in the armature, when 20 the circuits will be as indicated in Fig. 5. When the current in the armature circuit is thus reversed, the direction of current in the coil of the fixed solenoid 14 will also be reversed, with the result of changing the polarity of the latter so that poles of different signs of the respective solenoids 14 and 15 will be juxtaposed and the movable solenoid caused to rise and tend to shift the limit switches successively,—the service limit 25 switch A being first shifted, so that the circuits shall be as illustrated in Fig. 6, and immediately afterward the emergency limit switch will be shifted so that the circuit connections shall be as shown in Fig. 7,—the 30 latter figure of the drawing showing the circuits in lowering position with both switches reset.

From the above, it will be seen that the resetting of the limit switches is effected in 40 succession electrically, and that the same devices are also utilized in insuring the positive and effective engagement of the contacts of the switches when the latter are operated to effect the stopping of the motor and also 45 when they are shifted to normal position.

It will also be seen that at no place in the cycle of operation of the cut-out is the main line circuit opened.

Having fully described my invention what 50 I claim as new and desire to secure by Letters-Patent, is:—

1. In a motor control system, the combination with an electric motor, circuits therefor, and controlling means for said circuits, 55 of a limit switch, motor operated means for

shifting said switch to short circuit the motor armature, and electrically controlled means for resetting said switch when the controlling means are operated to reverse the current in the armature circuit. 60

2. In a motor control system, the combination with an electric motor, circuits therefor, and controlling means for said circuits, of two limit switches, motor operated means for shifting said switches, and means causing said switches to shift successively, first to short-circuit the motor armature and then to include both armature and field of the motor in a closed circuit, and means for resetting said limit switches. 65 70

3. In a motor control system, the combination with an electric motor, circuits therefor, and controlling means for said circuits, of two limit switches, motor operated means for shifting said switches to short-circuit 75 the motor armature and then include the field and armature of the motor in a closed circuit, electrically controlled means connected with said switches and operative to press movable contacts thereof against fixed 80 contacts, said electrically controlled means also operative to shift the switches to normal position when the current in the armature circuit is reversed by operation of said controlling means. 85

4. In a motor control system, the combination with an electric motor, circuits therefor, and controlling means for said circuits, of a limit switch, a fixed and a movable electro-magnetic device included in the motor 90 circuit and normally adapted to have repellent relation to each other, connections between the movable electro-magnetic device and said switch, means operated by the motor for shifting said switch to short-circuit 95 the motor armature, one of said electro-magnetic devices adapted to be included in the armature circuit, whereby when the current in said circuit is reversed by operation of the controlling means, the polarity of said electro-magnetic device will be changed and co-operation of the two electro-magnetic devices caused to reset the limit switch. 100

In testimony whereof, I have signed this specification in the presence of two sub- 105 scribing witnesses.

HARRY A. WACKERLY.
